UNITED STATES PATENT OFFICE.

ROBERT T. PARISEN, OF KNOXVILLE, PENNSYLVANIA, ASSIGNOR TO LAWSON MANUFACTURING COMPANY, OF HOMESTEAD, PENNSYLVANIA, A CORPORATION OF PENNSYLVANIA.

STAND-BOILER.

1,104,381.

Specification of Letters Patent. Patented July 21, 1914.

Application filed May 28, 1913. Serial No. 770,318.

To all whom it may concern:

Be it known that I, ROBERT T. PARISEN, a citizen of the United States, and resident of Knoxville, in the county of Allegheny 5 and State of Pennsylvania, have invented certain new and useful Improvements in Stand-Boilers, of which the following is a specification.

The primary object of this invention is 10 to provide a stand boiler of improved construction having a water heating coil located in a shell which is positioned within but closed to the boiler, whereby a relatively large area of heat-radiating surface is exposed to the water so that practically all 15 of the heat is utilized.

A further purpose is to provide a burner and combined burner-inclosing chamber and drip pan of novel construction, together with 20 improved means for securing the chamber as well as the boiler-supporting legs to the lower portion of the boiler.

In the accompanying drawings, Figure 1 is a front elevation of the improved boiler, 25 and Fig. 2 is a vertical longitudinal section of the same. Figs. 3 and 4 are sectional plan views taken on lines 3—3 and 4—4, respectively, of Fig. 1. Fig. 5 is a view of the burner-inclosing chamber detached from the 30 boiler. Fig. 6 is a sectional plan of the burner chamber taken on line 6—6 of Fig. 2. Fig. 7 is a vertical section of the burner and burner chamber taken on line 7—7 of Fig. 6.

35 Referring to the drawings, 2 designates a vertical shell of a cylindrical stand boiler of which 3 is the crown and 4 the bottom. The lower extremity of the shell is reinforced by the depending hoop-like rim 5, spot welded thereto at 5', and depending from the rim 40 are legs 6, the upper extremities of the legs being flanged at 7 to fit the inner face of the rim to which each is secured by a screw or bolt 8.

45 Within and closed to boiler 2 and open through the bottom thereof is cylindrical shell 9, and extending from the top thereof through crown 3 is vent pipe 10 which projects slightly above the crown with opposite 50 sides of the projecting portion slotted at 11. It will be understood that shell 9 and pipe 10 are sealed to the boiler interior and being surrounded by the water being heated a large area of heat radiating surface is ex-

posed to the water in addition to the water 55 heating coil presently to be described, thereby increasing the efficiency of the heating means.

Located within and depending from shell 9 is water heating coil 12 with the lower extremity thereof extended laterally at 13 and connected to bottom 4 by coupling 14. A drain 15 may be extended from coupling 14, as shown. The upper extremity of the coil is extended upwardly through vent 10, as 60 indicated at 16, and is bent laterally through one of slots 11 and connected by coupling 17 with crown 3, and this coupling may be utilized as a connection for the hot water service pipe 18. Cold water inlet may be 65 connected to the crown at the opposite side vent 10, in fact the crown openings may be used interchangeably for the hot and cold water connections.

70 Flue pipe 10' has a slip joint connection 75 with the slotted extremity of vent pipe 10 but is held by pipe 16 from fully covering slots 11, and the air admitted through the uncovered portions of the latter operates to check the draft upwardly through pipe 10. 80

The lower portion of the coil is inclosed by the burner chamber 20 having the open annular top portion 21 which connects with and forms a downward continuation of shells 9. Beneath rim 21 the chamber is 85 enlarged at one side at 22 to provide a frame for door 23, the door enlargement being curved complementary with rim 5. Projecting upwardly from the door enlargement are lugs 24 which engage the inner face of rim 5 90 with screws or rivets 25 extending through the rim and lugs, thereby supporting the chamber 20 in position to form a downward continuation of shell 9. Annular part 21 of the burner chamber is slotted at 26 to 95 embrace coil extension 13.

100 The ring-like gas burner 27 is adapted to be entered in the chamber through door 23 with the gas inlet tube 28 thereof extending through opening 29 in the bottom of chamber 20. The air inlet portion 30 of said opening is in line with vertical air passage 31 through burner 27, thereby supplying air in ample amount for combustion, the supply being supplemented by air admitted through 105 openings 30' in the wall of the chamber, also through openings 23' in the door.

Burner tube 28 is flanged on opposite sides

at 32 with the flanges entered in offsets 29' of opening 29, and the burner is secured by set screw 33' in lug 33 projecting from the chamber bottom. A mixer tube 34 is held in place in gas inlet 28 by set screws 35 carried by flanges 32, with gas supply pipe 36 extending to the mixer from gas regulating valve 37 having its thermostatic extension 38 fitted in boiler 2 with the valve controlling the flow of gas to the burner. The thermostatic valve may be of usual or any preferred construction.

Chamber 22, in addition to inclosing the burner, operates as a drip pan to catch and retain the condensate from the coil until it evaporates, flange 40 around bottom openings 29 and 30 and ledge-like flange 41 at the door opening preventing the water from running out. With the chamber beneath and in line with the coil the drippings are caught and confined in relatively close proximity to the burner and evaporate before there can be any overflow. Flange 40 serves to support the burner, as shown.

Water heating apparatus construction as herein shown and described is simple, durable and highly efficient. The parts thereof are easily accessible and may be readily assembled. The coil connections with the boiler are so arranged and located that they may be conveniently disconnected for renewing or repairing the coil.

I claim:—

1. The combination of a stand boiler, a chamber-forming shell within and closed to the boiler and open through the bottom thereof, a vent for the shell extending to the exterior of the boiler, a water heating coil within the shell with the upper extremity of the coil extending through the vent to the exterior of the boiler, coupling devices for connecting the upper and lower ends of the coil respectively to the upper and lower portions of the boiler, an open-top chamber beneath the boiler bottom and embracing the lower portion of the coil with the lower extremity of the latter extending through a wall of the chamber, and a gas burner within the chamber.

2. The combination of a stand boiler provided with a rim at its lower end offset downwardly from the boiler bottom, a chamber-forming shell within and closed to the boiler and open through the bottom thereof, a vent extending from the shell to the exterior of the boiler, an open-top burner-inclosing chamber forming a downward continuation of said shell, means securing the chamber to the bottom rim of the boiler, a water heating coil within the shell with its upper and lower ends connected respectively to the upper and lower portions of the boiler, and a gas burner within the burner-inclosing chamber.

3. The combination of a stand boiler, a

chamber-forming shell within and closed to the boiler and open through the bottom thereof, a vent extending from the shell to the exterior of the boiler, an open-top burner-inclosing chamber having a top portion of the same contour as the shell opening in the boiler bottom and uniting with and forming a downward continuation of the shell, the lower portion of the boiler formed with a downwardly extending rim, the burner-inclosing chamber shaped at one side to engage the rim with means for securing the chamber thereto, a water heating coil within the chamber-forming shell with its upper and lower ends connected respectively to the upper and lower portions of the boiler, and a gas burner within the burner-inclosing chamber.

4. The combination of a stand boiler, a chamber-forming shell within and closed to the boiler and open through the bottom thereof, a vent for the shell extending to the exterior of the boiler, a water heating coil within and depending from the shell with the upper end of the coil coupled to the upper portion of the boiler and with the lower extremity of the coil extended laterally and coupled to the lower portion of the boiler, an open-top burner-inclosing chamber secured to the boiler and forming a downward continuation of the shell, the chamber having an opening at one side to embrace the lateral extension of the coil, and a gas burner within the burner-inclosing chamber.

5. The combination of a stand boiler circular in cross-section, a chamber-forming shell circular in cross-section within and closed to the boiler and open through the bottom thereof, the location of the shell being eccentric to the boiler, a vent pipe extending from the shell to the exterior of the boiler, a water-heating coil within the shell with its upper and lower ends connected respectively to the upper and lower portions of the boiler, an open-top burner-inclosing chamber beneath the boiler and with its upper portion circular in cross-section and adapted to form a downward continuation of the shell, the boiler formed with a bottom depending rim, means securing the burner chamber to the depending rim, and a gas burner within the burner chamber.

6. The combination of a stand boiler, a chamber-forming shell within and closed to the boiler and open through the bottom thereof, a vent pipe extending from the shell to the exterior of the boiler, a water heating coil within the shell with its upper and lower ends connected, respectively, to the upper and lower portions of the boiler, the lower extremity of the boiler formed with a downwardly depending rim, legs for the boiler secured to said rim, an open-top burner-inclosing chamber forming a down-

- ward continuation of said shell, means securing the chamber to said rim, and a gas burner within the chamber.
7. The combination of a stand boiler, a chamber-forming shell within and closed to the boiler and open through the bottom thereof, a vent pipe extending upwardly from said chamber through the top of the boiler and projecting above the latter with the projecting portion slotted downwardly from its upper extremity, a water heating coil within the shell with the upper end of the coil extending through the vent pipe and laterally through the slotted extremity thereof, a coupling connecting the upper coil extremity with the top of the boiler, means connecting the lower coil extremity with the lower portion of the boiler, and coil heating means.
- 20 8. The combination of a stand boiler formed with a depending bottom rim, a chamber-forming shell within and closed to the boiler and open through the bottom thereof, a vent for the shell, a water heating coil within the shell and connected to the boiler, an open-top burner-inclosing chamber beneath the boiler and forming a downward continuation of said shell, lugs on the chamber fitting against the boiler rim, screws securing the lugs to the rim, and a burner within the said chamber.
- 25 9. The combination of a stand boiler, a chamber-forming shell within and closed to the boiler and open through the bottom thereof, a vent for the shell, a water heating coil within the shell and connected to the boiler, a burner chamber beneath and smaller than the boiler and in communication with said shell, the lower portion of the burner chamber enlarged at one side to provide a door frame, means for securing the burner chamber to the boiler, a burner within the

burner chamber, and a door fitting the door frame of the burner chamber.

10. The combination of a stand boiler, a vent pipe within the boiler and extending through the crown thereof and projecting thereabove with the projecting portion formed with lateral openings, a water heating coil having an extension thereof extending upwardly through the vent pipe and laterally through one of the openings in the projecting portion thereof, a flue pipe adapted to connect with the projecting portion of the vent pipe and bear against the out-turned extension of the coil with said extension preventing the flue pipe from entirely closing the openings in the vent pipe extension, and a coil heating burner from which products of combustion pass off through the said vent and flue pipes.

11. The combination of a stand boiler, a burner chamber beneath the boiler, the chamber bottom being open to admit fuel and the bottom being flanged upwardly around the opening for confining condensate dripping from the coil, a water circulating coil above the chamber bottom and operatively connected to the boiler, and a coil heating burner within the chamber.

12. In a water heater, the combination of a water circulating coil, a gas burner beneath the coil for heating the same, and a burner inclosing casing open at the bottom and with the bottom flanged upwardly around said opening for confining condensate dripping from the coil.

In testimony whereof I affix my signature in presence of two witnesses.
